Primary Examiner—Ted Shooman*Assistant Examiner*—Richelle Shelton*Attorney, Agent, or Firm*—Townsend and Townsend and Crew LLP[57] **CLAIM**

The ornamental design for a video and computer data recorder, as shown and described.

DESCRIPTION

FIG. 1 is a perspective view from above of a video and computer data recorder showing my new design;

FIG. 2 is a top plan view thereof;

FIG. 3 is a front elevational view thereof;

FIG. 4 is a right side elevational view thereof;

FIG. 5 is a right side elevational view thereof, with an open door;

FIG. 6 is a rear elevational view thereof;

FIG. 7 is a bottom plan view thereof; and,

FIG. 8 is a perspective view of a second embodiment of the video and computer data recorder with lighting surrounding the recording cartridge window, the other views being substantially the same as the first embodiment with the exception of the absence of the front, right side button. The broken line showing in Fig. 1 is for illustrative purposes only and forms no part of the claimed design.
